UNITED STATES PATENT OFFICE

132,714

DESIGN FOR A LAPEL BUTTON OR SIMILAR ARTICLE

Charles W. Coffield, Chicago, Ill.

Application February 6, 1942, Serial No. 105,679

Term of patent 3½ years

To all whom it may concern:

Be it known that I, Charles W. Coffield, a citizen of the United States, residing at Chicago, in the county of Cook and State of Illinois, have invented a new, original and ornamental Design for Lapel Buttons or Similar Articles, of which the following is a specification, reference being had to the accompanying drawing, forming part thereof.

Fig. 2 is a vertical central section, as viewed from the right-hand side of Fig. 1.

I claim:

The ornamental design for a lapel button or similar article, as shown.

CHARLES W. COFFIELD.
